INKSTAND

Gustav J. Sengbusch, Milwaukee, Wis.

Application March 15, 1940, Serial No. 324,167

4 Claims. (Cl. 120—59)

This invention relates to an improved inkstand of the type wherein there is an ink storage chamber and means for holding a pen with its pen point partially immersed in ink and in a readily accessible position so that upon withdrawal of the pen point, it is immediately ready for writing.

The main objects of the invention are to provide in an inkstand of the character indicated, means for holding the pen with its pen point in contact with ink in such a manner that an adequate but not an excess supply of ink will at all times be on the pen point, thereby to avoid objectionable accumulations of ink both on the pen point and lower portion of the pen holder and on the surrounding portion of the inkstand which holds the pen in accessible position; to provide an inkstand having the improved construction indicated which may be made economically and at low cost; and in general, it is the object of the invention to provide an improved inkstand of the character indicated.

In the drawing:

Figure 1 is a plan of the improved inkstand;

Figure 2 is a section on the line 2—2 of Figure 1, a portion of a pen being shown in operative relation to the inkstand;

Figures 3, 4 and 5 are front, side and bottom plan views, respectively, of a pen socket member comprising a part of the improved inkstand; and

Figure 6 is a section on the line 6—6 of Figure 4.

Referring now to the drawing, the improved inkstand comprises a receptacle member having an ink storage chamber 10, and an auxiliary chamber 11, such chambers being separated from each other by a partition wall 12. The receptacle comprising the chamber 10 and chamber 11 are preferably formed of hard rubber or other suitable material and it is preferably formed by a molding process. A weight 13 of metal or other suitable material may be sealed in the bottom portion of the member to prevent accidental tipping thereof. The weight 13 is preferably completely sealed from the ink chamber 10 so as to avoid corrosion of the metal and contamination of the ink; accordingly, a false bottom wall 14 is formed in the receptacle, the same being in effect molded integrally with the outside walls 15.

The partition wall 12 is provided with an opening 16 which establishes communication between the ink storage chamber 10 and the auxiliary chamber 11, said opening being of substantial proportions substantially as illustrated in Figures 1 and 2. Adjacent each side of the opening 16, the partition wall 12 is provided with lateral exten-

sions 17, 17 for a purpose which will presently appear.

The top wall 18 of the portion of the receptacle forming the auxiliary chamber 11 is provided with an opening 19 which is adapted to receive a generally cylindrical pen socket member 20. The socket member 20 is removably mounted on the inkstand by being snugly fitted in said opening 19 and the upper portion thereof which normally remains above the outside surface of the top wall 18 is provided with a pair of ears or lugs such as indicated at 21, 21 which facilitate manipulation of the removable socket member 20.

The socket member 20 is of such vertical dimension or length that its lower end 22 seats or very nearly seats on the bottom wall of the chamber 11. It is not important whether or not the lower end of the socket member 20 seats on the said bottom wall but it preferably reaches very nearly to said bottom wall. The socket may be adequately supported by providing its upper end with a shoulder such as indicated at 23 which is adapted to seat on the top of the chamber wall 18. The front ends of the partition wall extensions 17, 17, as shown in Figure 1, are so shaped either as a result of a drilling or molding operation or otherwise, as to be adapted to fit the outside surface of the adjacent portion of the socket member 20, and here again it should be observed that it is not of great importance whether or not a sealing contact is established between said partition portions 17, 17 and the socket member and that it is sufficient if these parts are so proportioned as to come very close to each other.

The socket member 20 is provided with an auxiliary inclined pen-receiving opening 24 which is provided with a flared upper end for facilitating insertion of a pen into the socket. The flared upper end of the pen-receiving opening 24 is further provided with a series of longitudinally extending ribs such as indicated at 25 for engaging circumferentially spaced portions of an end extension 26 of the pen holder 27, thereby to position the pen holder while at the same time maintaining space between the lower end portion of the pen holder and the socket wall, to maintain communication between the interior of the socket and the outside atmosphere. A shoulder such as indicated at 28 on the pen holder at the upper end of the cylindrical extension 26 thereof may serve to engage portions of the ribs 25 to limit insertion of the pen holder in the socket opening.

As best shown in Figure 2, the upper portion of the pen-receiving opening 24 is of such size

and shape that the wall of the opening is substantially spaced from the outer face or surface 29 of the pen point 20, which is carried by the pen holder. The socket opening, however, is of reduced cross-sectional dimension in its lower portion so that the lower end or nib portion 31 of the pen point is adapted to engage the inside wall portions 33 of the lower end of the socket on opposite sides of a narrow, slot-like opening 32 which is provided in said portion of the socket.

The lower portion of the pen-receiving opening 24 is defined by a wall part 33 so as to guide the pen point properly into its normal inclined position in the socket member with the nibs of the pen point in the described relationship to the walls of the socket on opposite sides of the slot 32. The wall 33, however, is provided with an aperture as indicated at 34 which serves to establish communication between the interior of the socket member 20 and the atmosphere outside of the inkstand. The space 35 inside of the socket member but outside of the pen-receiving opening 24 also communicates with the auxiliary chamber 11 through the side openings 36 formed in the cylindrical wall of the socket member. The pen-receiving opening 24 is open at its lower end as indicated at 37 so as to communicate with the interior space 36 of the socket.

The inkstand structure described is initially filled with ink by removing the socket member 20, holding the inkwell in a slanting position and pouring ink into the auxiliary chamber 11 through the opening 18. The ink will, of course, flow through the large opening 16 into the ink storage chamber 10. By tipping the inkstand to a vertical position, all of the ink poured into the auxiliary chamber 11 may be caused to flow into the storage receptacle 10 until the latter is substantially completely filled. Then by placing the inkstand in a horizontal position, ink would return from the storage chamber 10 to a depth which is determined by the vertical dimension of the opening 16. The pen socket 20 may then be inserted, whereupon the inkstand is ready for use.

When the pen socket 20 is inserted, it will be observed that the opening 16 in the partition wall 12 is substantially closed by the adjacent portion of the socket. Communication between the ink storage chamber 10 and the pen socket opening 24, however, is maintained through the agency of the slot 32.

It has been found that when a narrow slot such as 32 is provided for conducting ink from the reservoir 10 to the pen socket opening 24, the ink in the auxiliary chamber 11 will not reach the full depth of the vertical dimension of the opening 16 but that only a very shallow depth of ink will flow into the said auxiliary chamber. If the pen socket 20 is inserted in the receptacle before it is restored to normal, horizontal position, the ink flowing into the auxiliary chamber 11 will reach only such shallow depth. For example, in one specimen inkstand constructed substantially as shown and described, and of the proportions shown in the drawing, Figure 1 being substantially full-size, the opening 16 measures approximately $\frac{7}{16}$ " in depth and $\frac{1}{2}$ " in width, and with a socket member such as 20 having a slot measuring about $\frac{1}{16}$ " in depth and $\frac{3}{16}$ " in width, ink flowed from the storage chamber to the auxiliary chamber to a depth of about $\frac{1}{8}$ " or a little less, the pen being removed so as to avoid any obstruction to the normal flow of ink from the storage cham-

ber 10 to the auxiliary chamber 11. Such depth of the ink remained the same in the auxiliary chamber after a period of about forty-five days, during which a pen was repeatedly withdrawn and replaced during ordinary business usage of the inkstand.

The ink is conducted to the pen point to the full depth of the slot 32, apparently incident to the capillary effect of the narrow dimension of the slot 32, so that the pen point has delivered to it a substantial supply of ink adequate for ordinary writing purposes at one time. If the pen 27 is supplied with an ink reservoir arrangement such as shown in my Patent No. 1,915,338, the reservoir slots will also receive a supply of ink, apparently as a result of capillary action between the nibs of the pen point (the point being split as usual) whereby ink is carried upwardly to the usual hole 41. Ink may be transferred through the slit in the pen point and through the hole 41 to the inside surface of the pen point and the adjacent surface of the feed bar where further capillary action serves to convey ink to the various narrow ink-holding slots of the feed bar. In the present instance, a feed bar such as referred to is indicated at 39, such feed bar having a plurality of ink-holding slots such as indicated at 49.

The auxiliary chamber 11 is a desirable provision in desk sets of the character described in that it is adapted to receive ink discharged from the storage reservoir 10 incident to variations in atmospheric conditions. The auxiliary receptacle 11 serves as an overflow reservoir and thereby prevents an objectionable rise of the level of ink within the pen-receiving opening 24 and thereby prevents excessive wetting of the pen point, which may be said to be generally responsible for the presence of wet ink on the lower portion of the pen holder as is often found in most of the conventional inkstands heretofore available. The relatively large area of the auxiliary receptacle 11 makes negligible any rise in ink depth therein incident to atmospheric changes.

As to the reason for the shallow depth to which ink flows into the auxiliary chamber 11 from the storage chamber 10, there may be some uncertainty. However, it appears that because of the narrowness of the slot 32 which constitutes practically the only communicating opening between the ink storage chamber and auxiliary chamber, and the incident strength of the capillary action between the opposite walls of the slot, normal air pressure is not capable of displacing from the slot more than that portion of the ink contained within the indicated shallow-depth, lower portion of the slot to find its way into the ink storage chamber 10 so as to permit the out-flow of ink therefrom.

It will be apparent, of course, that the described arrangement for delivering ink to the pen point may be employed without having associated therewith the over-flow chamber 11, and that the pen-receiving socket member 20 is not necessarily made independently of the receptacle structure. It may be observed that the main receptacle may be filled with ink by pouring the same into the pen-receiving opening 24 of the socket while holding the inkstand in the inclined or vertical position above referred to. Such method of filling may be somewhat unsatisfactory, however, in that it would be a slow method because of the slowness with which ink would flow through the narrow slot 32.

Other changes in the described structure may

be made without departing from the spirit of the invention, the scope of which should be determined by reference to the following claims, the same being construed as broadly as possible, consistent with the state of the art.

I claim:

1. In an inkstand, a receptacle member having a main or ink storage chamber and an auxiliary chamber, there being a wall separating said chambers and provided with an opening for establishing communication therebetween, a pen socket removably mounted in said receptacle and entering and communicating with said auxiliary chamber, said socket having a portion overlying said opening so as to substantially close the same, said socket portion having a narrow slot therein adapted to receive ink from said storage chamber through said opening and operative to convey the ink to the interior of said socket, said socket being provided with an opening for venting said auxiliary chamber, thereby to enable the latter to receive ink discharged from said storage chamber incident to variations in atmospheric conditions whereby flooding of said socket is prevented.

2. An inkstand comprising an ink receptacle and a member for supporting a pen in said receptacle, said receptacle having an opening for receiving said member with its axis in substantially right-angular relation to the normal plane of the receptacle, and said member having a pen receiving socket axially inclined relative to the normal axis of the member for supporting the pen in inclined position.

3. An inkstand comprising an ink reservoir,

an overflow chamber, said reservoir and chamber being separated by a partition wall provided with an opening establishing communication between said reservoir and chamber, and a pen receiving socket, said overflow chamber being provided with an opening therein for receiving said socket and positioning the same with a wall portion thereof substantially closing said partition wall opening, said socket wall portion being provided with a passageway of small size relative to the size of said partition wall opening to permit restricted flow of ink from said reservoir into said socket.

4. An inkstand comprising an ink reservoir, an overflow chamber, said reservoir and chamber being separated by a partition wall provided with an opening establishing communication between said reservoir and chamber, and a pen supporting member, said overflow chamber being provided with an opening therein for receiving said pen supporting member with a wall portion thereof substantially closing said partition wall opening, said wall portion being provided with a passageway of small size relative to said partition wall opening to permit restricted flow of ink from said reservoir into said pen supporting member, said member having a partition element cooperating with said wall portion to form at least a part of a socket for receiving and supporting a pen, said partition element terminating at its lower end intermediate the upper limit of said passageway and the lower limit of said opening.
